Patented Nov. 13, 1973

229,183

TABLE TOP AIR CIRCULATOR

Georg F. Papst, 7742 St. Georgen,
Black Forest, Germany

Filed Dec. 15, 1971, Ser. No. 208,524

Term of patent 14 years

Int. Cl. D23—04, 03
U.S. Cl. D23—155

FIG.1

FIG. 2

FIG. 3

FIG.4

FIG.5

FIG. 6

FIG. 7

FIG. 9

FIG.10

FIG.11

FIG. 1 is a top front perspective view of a table top air circulator showing my new design;

FIG. 2 is a left end elevational view thereof;

FIG. 3 is a top plan view thereof;

FIG. 4 is a bottom plan view thereof;

FIG. 5 is a right end elevational view thereof;

FIG. 6 is a right side elevational view thereof;

FIG. 7 is a left side elevational view thereof but turned in an opposite direction;

FIGS. 8, 9, 10 and 11 are perspective views of other embodiments of my new design.

The electrical connector and cord are omitted in FIGS. 2, 3, 4, 5 and 6 for convenience of illustration.

I claim:

The ornamental design for a table top air circulator, as shown and described.
